Primary Examiner — Ramzi S Almatrahi(74) *Attorney, Agent, or Firm* — Ewers & Hasselmann PLLC(57) **CLAIM**

The ornamental design for a video centration apparatus, as shown and described.

DESCRIPTION

FIG. 1 is a front elevation view of a video centration apparatus;

FIG. 2 is a front perspective view thereof;

FIG. 3 is a left side elevation view thereof;

FIG. 4 is a right side elevation view thereof;

FIG. 5 is a rear elevation view thereof;

FIG. 6 is a top plan view thereof; and,

FIG. 7 is a bottom plan view thereof.

The broken lines depict portions of the video centration apparatus in which the design is embodied that form no part of the claimed design.
